The ornamental design of the pedicure spa, as shown and described.

DESCRIPTION

FIG. 1 is a front, left and top perspective view of a pedicure spa showing my new design;

FIG. 2 is a top view of the pedicure spa, such as that shown in FIG. 1;

FIG. 3 is a left side view of the pedicure spa, such as that shown in FIG. 1;

FIG. 4 is a right side view of the pedicure spa, such as that shown in FIG. 1;

FIG. 5 is a front view of the pedicure spa, such as that shown in FIG. 1; and,

FIG. 6 is a rear view of the pedicure spa, such as that shown in FIG. 1.

The broken lines shown are for illustrative purposes only and form no part of the claimed design.
